US0D1100195S

(12) **United States Design Patent** (10) **Patent No.:** **US D1,100,195 S**
(45) **Date of Patent:** **** Oct. 28, 2025**

(54) **TENSIONER**

(71) Applicant: **Vilex LLC**, Park City, UT (US)

(72) Inventors: **Brock Johnson**, McMinnville, TN (US); **Daniel J. Triplett**, Smithfield, UT (US)

(73) Assignee: **Vilex LLC**, Park City, UT (US)

(**) Term: **15 Years**

(21) Appl. No.: **29/853,810**

(22) Filed: **Sep. 19, 2022**

(51) LOC (15) Cl. **24-02**

(52) U.S. Cl.

USPC **D24/133**

(57) **CLAIM**

The ornamental design for a tensioner, as shown and described.

DESCRIPTION

FIG. 1 is a perspective view of a tensioner.

FIG. 2 is a front view of a tensioner.

FIG. 3 is a rear view of a tensioner.

FIG. 4 is a left side view of a tensioner.

FIG. 5 is a right side view of a tensioner.

FIG. 6 is a top view of a tensioner; and,

FIG. 7 is a bottom view of a tensioner.

The broken lines depict portions of the tensioner that form no part of the claimed design.

1 Claim, 5 Drawing Sheets
